ADJUSTABLE MOUNTING FOR DITCHING
WHEEL EXCAVATORS

Robert N. Bennett, McComb, Ohio, assignor to
Gar Wood Industries, Inc., Detroit, Mich., a
corporation of Michigan

Application November 21, 1946, Serial No. 711,358

5 Claims. (Cl. 37—97)

1

This invention relates to digging machines and particularly to a machine in the nature of a road widener for excavating and leveling the ground immediately adjacent the road pavement to form a berm or to receive a pavement widening strip.

An object of this invention is to produce a new and improved machine of this type in which a digging wheel is adjustably mounted on the tractor in driving connection with its power source for operating on the road berm while the tractor is traveling in a manner not to interfere with normal road traffic, the digging wheel being shiftable through an arc of 90° to inoperative or traveling position.

Another object is to produce a digging attachment which is mounted on a traction machine in a manner to enable positioning thereof to one side and to the rear of the traction machine for operation on the side of the road adjacent that on which the machine is traveling, to enable vertical adjustment in the direction toward or away from the ground while so positioned, and to enable positioning of the attachment in lengthwise alignment onto the rear of the traction means while inoperative, thereby, in that position, to conform more substantially to the width of the traction machine to obviate road hazards while traveling from place to place.

A further object is to produce an improved means for mounting a digging attachment onto the rear of a truck, which enables shifting of the attachment between the operative and traveling positions with the expenditure of a minimum of time and labor while enabling vertical adjustment thereof in either position, the attachment being such as to militate against binding, distortion or excessive strain on the parts when the machine is operating over uneven surfaces.

Other objects and advantages of the invention will hereinafter appear, and for purposes of illustration but not of limitation, an embodiment of the invention is shown in the accompanying drawings in which

Figure 1 is a rear perspective view of a road widener with the excavating attachment mounted in the operative position at the side of the truck;

Figure 2 is an enlarged detail side elevation of the excavating attachment in operative position at the side of the truck, only a fragment of the truck being shown; and

Figure 3 is a top plan view of the excavating attachment, shown in solid lines in the operative position, and in broken lines in the traveling

2

position, with parts removed more clearly to illustrate the mounting structure.

The structure embodying the invention comprises a digging attachment A, which is carried by an auxiliary frame B mounted on the rear of a truck or tractor chassis C. The truck chassis C is supported at the front by steering wheels W and at the rear by tandem traction wheels T and is provided with a power source P, which is adapted to drive both the traction wheels T and the digging mechanism. The digging attachment A is vertically adjustable relative to the auxiliary frame B and is adapted to be shifted laterally of the frame for disposition in the operative position, and to be disposed in alignment with the frame in the inoperative position, as will hereinafter be explained.

The auxiliary frame B conforms generally to the rectangular contour of the truck chassis C and includes a pair of lengthwise stringers 1, fixed at their forward ends to the upper terminals of vertical posts 2, which are secured to intermediate portions of longitudinal channel members 3 of the chassis frame. The rearward ends of the stringers 1 are secured to upper portions of upright pillars 4, which are respectively rigidly mounted on crosswise frame members 3a of the chassis frame. Bracing each of the stringers 1 are inclined beams 5 and 6, which diverge from intermediate portions of the stringers and connect at their lower ends to the corner sections formed of the adjacent posts 2 and pillars 4 with channel members 3. The stringers 1 are transversely braced by a cross member 7, and an X-frame 8 reinforces the upright pillars 4.

The digging attachment A is carried by an upright tubular column 9, which is held in fixed position by upper and lower brackets 10 and 11 respectively. These brackets are secured between pairs of converging metal plates 12 and 13, which extend crosswise of and beyond one side of the frame and are rigidly secured to the opposite ends of the pillars 4. Cross members 14 and 15 further reinforce the pillars at their respective upper and lower end portions. At the upper end portion another plate 12' is arranged between the plates 12 and parallel to one of them and is welded to an auxiliary cross member 14'. The cross member 14' is rigid with the pillars 4. A top plate 15' is secured to the box-like structure above described.

In the excavating position, the digging attachment A is disposed to one side and rearwardly of the column 9 and has a rectangular digging

wheel frame 16. The frame 16 has at its forward inner end a rigid housing 17, which is rigid with the lower portion of a vertically disposed elongate sleeve 18. The sleeve 18 slides on and can rotate about the column 9. The rear of the frame 16 is supported by an inclined tubular strut 19, which projects through and is slidable relative to an upwardly and rearwardly inclined extension bracket 20 on the frame, a pair of collars 21 adjustable on the strut providing stops for limiting the relative movement of these parts. Manifestly, when the digging wheel frame is elevated, the bracket 20 engages the lower of the collars 21 which thereby assists in sustaining the weight of the outer frame portion. The other end 22 of the strut 19 is pivotally secured to the upper end portion of the sleeve 18. The outer side of the frame 16 is supported by an upright hangar bar 23, which is pivotally secured at its lower end to an extension 24 on the outer front portion of the frame 16 and is adjustably engaged at its threaded upper end 25 by a bracket 26. In machines of this character, a certain amount of play is allowed in some joints and, although this is not sizable, nevertheless it is such as to make possible slight angle frame adjustments made possible by the threaded end 25 of the hangar bar 23. The bracket 26 has a pair of laterally extending divergent truss members 27 and 28, which are secured to upper and intermediate portions respectively of the sleeve 18. Thus, upon movement of the sleeve vertically on its supporting column 9, the digging attachment is concomitantly adjusted in the direction toward or away from the ground.

In order to hold the digging attachment A in fixed relation to the tractor frame, there is provided an elongate housing 30, which forms a part of the digging wheel frame 16. The housing 30 extends laterally across the frame and rigidly connects the front ends of longitudinal frame beams 31. A telescoping shaft 32 extends into the housing a substantial distance when the digging wheel is in position of use. The shaft 32 extends through an end cap 33 of the housing and attached to the outer end of the shaft is a stop plate 34, a guide bracket 34a within the housing snugly embracing and guiding the shaft. An arm 35 is rigid with and extends perpendicularly from the free end of the shaft 32 and is engageable with a yoke 36 so that apertures in the ends of the arm and the yoke 36 are in registry so that a removable pin 37 may be inserted therethrough. The yoke 36 is secured to the rear wall of rearwardly extending triangular slide bracket 38, which is slidable vertically on the left-hand pillar 4 (Figure 1). The arm 35 is provided with a straight end wall 39 to enable abutment with a substantial portion of the inner face of the yoke 36, thereby to militate against relative movement of the arm 35.

The sleeve 18 and the slide bracket 38 are adjustably suspended by a pair of hoist cables 40 and 41. The cable 40 is anchored at one end to an intermediate portion of the slide bracket 38 and the other end is fixed to a drum 42. The drum 42 rotates with a shaft 43, which is journaled between upper portions of the pillars 4. The other cable 41 is anchored at one end to an intermediate portion of the sleeve 18, thence passes over a pair of sheaves 45 and 46 rotatably mounted on shafts positioned between the upper extension plates 12 and 12', and then downwardly to a drum 48 on an end portion of the shaft 43. A cable 49 extends from a drum 50 secured to the

other end of the shaft 43 and to a winch 51 which is suitably driven in one direction or the other by the power plant P.

As illustrated, when the winch 51 is rotated in a counterclockwise direction (Figure 1), the drum 50, drums 42 and 48 are similarly rotated to wind up the cables 40 and 41 and raise simultaneously the sleeve 18 and slide bracket 38. Manifestly, by rotation of the winch 51 in the opposite direction, the parts are lowered to dispose the excavator in position of use.

The excavating means in the form of a digging wheel is mounted for rotational movement within the frame 16 and comprises a pair of annular rim members 52 and 53 which are laterally spaced a distance corresponding to the width of the strip it is desired to dig. The rim members are connected by an annular series of excavating buckets 54, which are provided with outwardly projecting rooters 55. The digging wheel is supported in the frame 16 at three spaced apart points, two of which comprise guide rollers 56 and 57 which engage the inner edge of the rim members and are adjustably mounted in a suitable framework 58 carried by the frame 16. The third point of support consists of a gear 59 mounted on a drive shaft 60 which is journaled in the frame 16 to extend transversely therethrough and in driving engagement with teeth 61 arranged in an annular row on the rims 52 and 53.

On the inner end of the shaft 60 there is a sprocket wheel (not shown) connected by a sprocket chain 63 to another sprocket wheel 64 secured to the outer end of a shaft 65 which is journaled in a transmission housing 66 fixed to the top of the housing 17. A sprocket chain 67 connects a sprocket 68, on the other end of the shaft 65, sprocket wheels 69 and 70, and a sprocket wheel 71, the latter being suitably driven from the power source P through a suitable transmission F. The sprocket 69 is mounted on the adjacent pillar 4, and the sprocket 70 is mounted on the end of a pivotally mounted arm 72. The arm 72 is urged to swing in a clockwise direction (Figure 2) by a coil spring 73 thereby constantly to tension the chain 67 in any relative position of adjustment of the digging wheel.

An endless conveyor belt 75 is guided over rollers 76 and 77, which are journaled in suitable bearing brackets 78 secured to the frame beams 31, and extends transversely through the digging wheel to carry the spoil delivered by the digging buckets to the outer side of the machine. Guide aprons 79 and 80 are mounted on opposite sides of the upper run of the belt. The conveyor belt 75 is driven by the inner roller 76, which in turn is operated by the driving shaft 65 through suitable gearing in the transmission housing 66.

Suspended from the rear of the digging wheel frame 16 by a suitable support 81 is a shoe 82, which is adapted to ride on the bottom of the trench in close proximity to the digging wheel, so that, in combination with a shroud 83, the loose and unexcavated material is placed in a position where it will be removed by the revolving buckets 54.

When not in use, the digging wheel A is adapted to be swung about the column 9 and into lengthwise alignment with the truck body, thereby reducing the over-all width of the machine for traveling purposes. To move the wheel to such position, the arm 35 is disconnected from the yoke 36 by removal of the pin 37. The shaft 32 is then further telescoped into the housing 30 to the extent permitted and the sprocket chain 67

is disengaged from the sprocket 68. The digging wheel can now be readily swung about the column 9 through an arc of about 90° until an apertured plate 84 welded in proper position on the inner frame beam 31 is disposed between the yoke 36. The pin 37 is then inserted through the registered apertures for locking the digging wheel and associated parts in traveling position. Since the slide bracket 38 and the frame 16 move vertically together, engagement of the plate 84 with the yoke 36 can be effected in any position of vertical adjustment.

From the above description, it is apparent that when the digging wheel is mounted on the rear of the truck in the inoperative or traveling position, the truck may be driven on the road from place to place without disturbing the road traffic, because in that position, its wheel axis is in lengthwise alignment with the truck and only a small portion of the attachment extends laterally of the truck body. Since the digging wheel frame 16 is firmly engaged at two points, which are simultaneously vertically adjustable, vertical adjustment may still be readily effected in the inoperative position without disturbing the mounted relation.

When the digging wheel is in the operative position, its wheel axis is transverse with the truck and it is operative on the side of the road closely adjacent that on which the truck is traveling. This enables excavating a trench in parallel relation with the truck movement while traveling in its proper position on the road. The conveyor is adapted to receive the excavated material and deposit it on the far side of the excavated trench so that in operation, no hazard or obstruction to normal road traffic is produced. The excavating wheel is readily adjusted vertically by operation of the winch 51 in one direction or the other to increase or decrease the depth of the trench.

It is manifest that I have produced a road widening machine adapted to excavate a trench along one side of a highway for receiving a widening strip of pavement while the truck is traveling in its normal road position. New and improved mounting means are provided which enable the excavating attachment to be vertically adjusted while in the operative or inoperative position, and to be positioned in lengthwise alignment with the truck while inoperative or swung through an arc of 90° to the excavating position through the expenditure of a minimum of labor and time; and which enables the machine or excavating attachment to operate over uneven surfaces without impairing the alignment or operation of the parts.

It is to be understood that numerous changes in details of construction, arrangement and operation of the parts may be effected without departing from the spirit of the invention especially as defined in the appended claims.

What I claim is:

1. A road widening machine comprising a truck, an excavating wheel, said truck having a frame carrying said wheel, a supplemental frame including an extension at the rear of said frame, a pivotal mounting at one side of said extension, a yoke carried by said extension, a housing forming part of said excavating wheel frame, a telescoping member shiftable in said housing and adapted to be rigidly attached to said yoke when in operative position and to militate against swinging movement and upon disengagement from said yoke said excavating wheel frame is enabled to be swung to an inoperative position

to the rear of said extension with the axis of said excavating wheel substantially parallel to the longitudinal plane of the truck, and an extension on said excavating wheel frame adapted to be rigidly attached to said yoke when in inoperative position.

2. A road widening machine comprising a truck, a supplemental frame mounted on the truck chassis and forming an extension at the rear and at one side of the truck, said extension having a vertical guide means, a digging wheel, a digging wheel frame for said digging wheel carried by said guide means in a manner enabling the digging wheel to be disposed at one side of the truck for digging purposes and to be swung through an angle of about 90° to the traveling position on the rear of the truck and in either position of horizontal adjustment to be vertically positioned relative to the truck, means for raising and lowering the digging wheel frame relative to the truck, and means for holding the digging wheel frame in the desired position of horizontal adjustment, the means for positioning the digging wheel frame in the desired position of horizontal adjustment comprising a housing which extends transversely across the digging wheel frame, a telescoping member adapted to extend laterally from said housing when in the digging position, and means on the other side of said supplemental frame adapted rigidly to engage said telescoping member when in the excavating position and an intermediate portion of said digging wheel frame in the traveling position.

3. A road widening machine comprising a truck, a supplemental frame mounted on the truck chassis and forming an extension at the rear and at one side of the truck, said extension having a vertical guide means, a digging wheel, a digging wheel frame for said digging wheel carried by said guide means in a manner enabling the digging wheel to be disposed at one side of the truck for digging purposes and to be swung through an angle of about 90° to the traveling position on the rear of the truck and in either position of horizontal adjustment to be vertically positioned relative to the truck, means for raising and lowering the digging wheel frame relative to the truck, and means for holding the digging wheel frame in the desired position of horizontal adjustment comprising a housing which extends transversely across the digging wheel frame, a telescoping member adapted to extend laterally from said housing when in the digging position, and means on the other side of said supplemental frame adapted rigidly to engage said telescoping member when in the excavating position and an intermediate portion of said digging wheel frame in the traveling position, the means for positioning the digging wheel frame in the desired position of horizontal adjustment comprising a housing which extends transversely across the digging wheel frame, a telescoping member adapted to extend laterally from said housing when in the digging position, and means on the other side of said supplemental frame adapted rigidly to engage said telescoping member when in the excavating position and an intermediate portion of said digging wheel frame in the traveling position, said means being vertically adjustable with said digging wheel frame.

4. A road widening machine comprising a truck, a supplemental frame mounted on the truck chassis and forming an extension at the rear and at one side of the truck, said extension having a vertical guide means, a digging wheel, a digging wheel frame for said digging wheel carried by said guide means in a manner enabling the digging wheel to be disposed at one side of the truck for digging purposes and to be swung through an angle of about 90° to the traveling position on the rear of the truck and in either position of horizontal adjustment to be vertically positioned relative to the truck, means for raising and lowering the digging wheel frame relative to the truck, and means for holding the digging wheel frame in the desired position of horizontal adjustment comprising a housing which extends transversely across the digging wheel frame, a telescoping member adapted to extend laterally from said housing when in the digging position, and means on the other side of said supplemental frame adapted rigidly to engage said telescoping member when in the excavating position and an intermediate portion of said digging wheel frame in the traveling position, 75 and lowering the digging wheel frame relative to

the truck, and means for holding the digging wheel frame in the desired position of horizontal adjustment, the horizontal positioning means comprising an extension on the rear of said supplemental frame which extension is vertically adjustable with said digging wheel frame, a yoke carried by said extension, a housing forming a part of said digging wheel frame, a telescoping member shiftable in said housing and adapted to be rigidly attached to said yoke when the digging wheel frame is in the digging position to militate against swinging movement, said telescoping member being disengageable from said yoke to enable the digging wheel frame to be swung to the traveling position, and an extension on said digging wheel frame adapted to be rigidly attached to said yoke when in the traveling position.

5. A road widening machine comprising a truck, a supplemental frame mounted on the truck chassis and forming an extension at the rear and at one side of the truck, said extension having a vertical guide means, a digging wheel, a digging wheel frame for said digging wheel carried by said guide means in a manner enabling the digging wheel to be disposed at one side of the truck for digging purposes and to be swung through an angle of about 90° to the traveling position on the rear of the truck and in either position of horizontal adjustment to be vertically positioned relative to the truck, means for raising and lowering the digging wheel frame relative to

5 the truck, and means for holding the digging wheel frame in the desired position of horizontal adjustment, the horizontal positioning means comprising an extension on the rear of said supplemental frame which extension is vertically adjustable with said digging wheel frame, a yoke carried by said extension, a housing forming a part of said digging wheel frame, a telescoping member shiftable in said housing and adapted to be rigidly attached to said yoke when the digging wheel frame is in the digging position to militate against swinging movement, said telescoping member being disengageable from said yoke to enable the digging wheel frame to be swung to the traveling position, and an extension on said digging wheel frame adapted to be rigidly attached to said yoke when in the traveling position, and the raising and lowering means comprising hoist means for vertically adjusting said digging wheel frame and the second mentioned extension together.
